REVOLVING TURRET ASSEMBLY AND
ANCHORAGE

Edward Balstad, Philadelphia, Pa.

Application May 6, 1943, Serial No. 485,837

8 Claims. (Cl. 308—231)

This invention relates to rotary turrets and is concerned primarily with the provision of certain improvements in a turret construction of the type illustrated and described in the co-pending application of Edward Balstad, Serial No. 414,375, filed October 9, 1941, and entitled "Revolving turret assembly and anchorage."

For many years warships of the various classes from battleships down to gunboats have been provided with rotary turrets upon which are mounted guns and protecting armor, as well as the various mechanisms employed in loading and elevation operations incident to firing. While various improvements have been suggested from time to time to eliminate certain difficulties which have been recognized to exist, there has been, as a practical matter, very little change in the designs of these turrets; and until the advent of the invention disclosed in the above identified co-pending application, there has been no practical solution to certain well recognized existing problems.

A rotary turret ordinarily includes a platform which carries the guns and which may be rotated to proper position for firing the guns, and this platform must bear the strains and stresses incident to the recoil of the guns at the time of firing. Obviously, it is highly important that the platform remain over an extended period of time in its initial stationary condition and not be thrown out of order due to breakage of parts, excess deflection, and premature wear, since any of these factors tends to decrease the effectiveness of gun fire, and, in extreme cases, may render the guns useless.

Because of this need, and further in view of the enormous load which the platform must support, it has been the practice to mount the platforms on roller bearing assemblies with which are associated retaining devices such as clips, which maintain the platform in proper position, particularly during firing of the guns. The recoil of gun fire tends to depress one edge of the gun platform and elevate the diametrically opposite edge. The said co-pending application provides retaining clips which results in an arrangement which is highly improved as compared with anything previously known. These retaining clips are positioned at the outermost peripheral edge of the gun platform and take advantage of the longest possible lever arm in reducing tilting stresses to a minimum.

The present invention has in view, as a highly important object, the provision of a turret construction of the character aforesaid, which includes an improved arrangement for lubricating the roller bearing assembly that supports the gun platform. Heretofore, it has been the practice to employ a relatively heavy grease for this purpose. Inasmuch as the rollers are not in-

closed, the grease picks up dirt and splinter fragments which not only seriously impair the lubricating effects, but actually functions as a grinding solution rather than a lubricant. In accordance with this invention, the roller bearing assembly is completely inclosed and immersed in a bath of lubricating oil. Important detailed objects and advantages of the invention are associated with the provision of the oil seals for accomplishing this arrangement.

Another important object of the invention is the provision of improvements in the roller bearing assembly itself. With the gun platform supported upon the rollers, it is obvious that the crest or top line of tangential contact with the gun platform takes its proportionate share of the load. It is therefore believed to be highly advantageous to provide a roller bearing assembly in which it is possible and entirely practical to employ a larger number of rollers than has heretofore been thought possible. Thus, the weight of the loading platform is distributed over a greater number of bearing elements. It is equally important to at the same time provide for the easy and quick removal of any desired roller or rollers which might become damaged or worn, and while the track elements between which the rollers are interposed remain in their relative positions.

Yet another object of the invention is the provision of a rotary turret of the character aforesaid, including a roller bearing assembly made up of rollers, each of which comprises two complementary conical elements, which interfit and with which is associated a spring tending to maintain the conical elements in a desired relative position. The springs included in these rollers are particularly important as they insure a proper centering of the turret pan plate, regardless of disturbing forces such as the listing of a ship on which the turret is mounted.

Various other more detailed objects and advantages of the invention, such as arise in connection with carrying out the above noted thoughts in a practical embodiment, will in part become apparent and in part be hereinafter stated, as a description of the invention proceeds.

The invention, therefore, comprises an improved rotary turret construction in which the roller bearing assembly is enclosed and immersed in a lubricating bath. The roller elements of the roller assembly each comprises two complementary interfitting parts together with a spring.

For a full and more complete understanding of the invention, reference may be had to the following description and accompanying drawing, wherein:

Figure 1 is a top plan view of a turret pan plate with certain parts broken away;

Figure 2 is a detailed view of the roller bearing assembly employed beneath the pan plate;

Figure 3 is an enlarged detailed vertical section taken through the roller bearing assembly and immediately associated parts. This view is taken about on the plane represented by the line 3-3, Figure 1; and

Figure 4 is an enlarged detailed view, partly in section, and partly in elevation, bringing out the joint construction in the oil seal rings.

Referring now to the drawing, wherein like reference characters denote corresponding parts, and first more particularly to Figure 1, a turret pan plate is identified by the reference character 10 and is generally a rotating platform upon which the guns and various associated parts are carried. This pan plate 10 is of a smaller diameter than the design now being commonly used. A revolving or movable trackway 11 supports the outer peripheral edge of the pan plate 10 and is joined thereto by the welded joints shown at 12 and 13. An inner bulkhead 14, that is substantially circular in formation, upstands from the inner edge of the ringlike trackway 11 and is positioned by its engagement with a shoulder 15 formed in the trackway 11 and held in this position by welded joints shown in 16 and 17. An outer conical bulkhead 18 is similarly positioned against a shoulder 19 of the trackway 11 and the welds 20 and 21 maintain the assembled relation. Radial webs 22 extend between the bulkheads 14 and 18 and are welded both to these bulkheads and the trackway 11.

The underface of the trackway 11 includes a roller raceway 23 which is slightly inclined as illustrated. This raceway 23 is designed for the reception of a giant roller bearing assembly made up of a plurality of individual rollers, each of which is referred to in its entirety by the reference character R. It is evident that the weight of the rotary trackway 11, pan plate 10, and their connected parts, is borne by the crest of the rollers R.

A lower stationary trackway 24 is provided with an upper inclined bearing raceway 25 which also receives the roller bearing assembly made up of the rollers R. This lower trackway 24, of course, supports all the weight of the rotary parts that are carried by the roller bearing assembly.

This stationary track 24 is ringlike in shape and is supported by a ringlike conical bulkhead or turret foundation, such as depicted at 26 and 27. The outer peripheral edge of the lower trackway 24 carries a ringlike block 28, which may be made in sections and which is removable from the trackway 24. This block is normally held in position by bolts 29 and functions as a guide or retainer for the rollers R.

At the time of gun fire, there is a decided tendency of the upper trackway 11 to tilt and raise one portion, while the diametrically opposite portion tends to dip. In order to minimize the reaction of such a twisting force, there is provided a series of retaining or holding down clips 30 around the entire periphery of the tracks. These holding down clips 30 are shown as bolted to the stationary track 24 by the bolts 31, and each clip 30 includes inwardly extending flanges 32 and 33, which engage the tracks 11 and 24 respectively. If any vertical adjustment of the holding down clips becomes necessary, shims may be inserted between the flange 33 and the stationary track 24.

As is clearly brought out in Figure 3, the cir-

cular bulkhead 34 depends from the inner edge of the rotary track 11, and may be anchored thereto in any preferred manner, as by the bolts shown at 35.

While the slight conical taper of the rollers R, together with the inclination of the tracks 11 and 24, would tend to keep the rotary track in a centered relation with respect to the stationary track, additional means to maintain this relation is highly desirable in view of the displacing force exerted at the time of gun fire. Thus, a ring 36 is shown as anchored to the underface of the rotary track 11 as by webs 37. This ring 36 includes the outer peripheral bearing surface 38, which receives lateral support at the time of gun fire from a sectional thrust bearing 39, that is carried by the stationary track 24, adjacent to its inner periphery.

The inner portion of the stationary track 24 is undercut as shown at 40 to provide a cam-like shelf which receives the thrust bearing 39. The latter is of a sectional construction, and may be made of bronze.

Referring for the moment to Figure 2, it will be noted that the rollers R are maintained in assembled relation by overlapping links 41 which receive the ends of the roller shafts, which will be later described.

Referring now again to Figure 3, each of the rollers R is shown as comprising a main body part 42, formed with a bore 43 through which passes a roller shaft 44. The bore 43 is enlarged to provide a counterbore 45. Received in this counterbore 45 is a plug extension 46 carried by a roller thrust collar 47. The collar 47, together with the plug extension 46, is provided with a bore which receives the shaft 44. A compressed spring shown at 48 is positioned in the counterbore 45 and normally exerts a tendency to spread the thrust collar 47 from the main body portion 42 of the roller. A dowel pin shown at 49 is received in aligned recesses in a main body portion 42 and thrust collar 47 to prevent relative rotation between these parts.

It is evident that the extremities of the roller shaft 44 are received in aligned openings in the overlapping links 41. Spacer rings such as shown at 50 may be interposed between the end portions 50 of the shaft and the links. Lock nuts 51 are threaded on the end of the shafts 44 and maintain the assembled relations of the parts of each roller. If it becomes necessary to adjust any of the rollers R, either by contracting the parts 42 and 47, or expanding them, as in compensating for wear, this may be accomplished by either tightening or loosening the nuts 51 as the case may be.

It is particularly important to note that the rollers do not take the horizontal forces set up by gun fire. It is true that the thrust collar 47 and main body part 42 are initially compressed, but when the ring 36 engages the thrust bearing 39, the horizontal force of the gun fire will be taken by these elements rather than by the rollers.

To provide for the complete enclosure of the roller bearing assemblies, an oil pan 52 is shown as extending between the stationary track 11 and the ring 36, which is carried thereby. An oil seal 53 is positioned to seal the space between the ring 36 and the lower stationary track 24. Another oil seal 54, of generally similar construction, seals the space between the flanges 32 of the clips 31 and the upper track 11.

Each of the oil seals 53 and 54 comprises a sec-

tional ring, the various sections of each having complementary bevelled ends, as shown at 55 in Figure 4. These bevelled ends are formed with aligned openings 56 and bolts 57, pass through these aligned openings 54, and are anchored to the respective track. Coil springs shown at 58 are disposed about each of the bolts, and, by their expansive force, tend to urge the oil seal rings into sealing position.

Through long continued use, or for other reasons, it may be necessary from time to time to replace certain parts of the above described mechanisms, and provision is made for simple and quick removal when necessary. The removal of any of the rollers from between the two tracks 11 and 24 requires that the bolts holding any particular section of the block or ring 28 be taken out so that that section may be removed. The nut 51 is then taken from the damaged roller, as is the nut from the roller on each side of the damaged one. The links 41 are then manipulated so that the outer end of the damaged roller receives no lateral support and is free to move outwardly as soon as the inner nut 51 and inner links 41 are similarly removed. Just as it is necessary to first remove the holding clips 30 in order to take off the outer nuts 51, it is also necessary to remove the oil pan 52 to obtain access to the inner nuts 51.

Due to the fact that the rollers are frusto conical in shape with their inner ends of smaller diameter, a slight tilting of the rollers will aid with their quick removal, even though the space is restricted.

While a preferred specific embodiment of the invention is hereinbefore set forth, it is to be clearly understood that the invention is not to be limited to the exact constructions illustrated and described, because various modifications of these details may be provided in putting the invention into practice, within the purview of the appended claims.

What is claimed is:

1. In a turret construction of the character described, a movable trackway formed with a roller raceway, a stationary trackway spaced from said movable trackway and formed with a roller raceway opposite to said raceway on said movable trackway, a roller bearing assembly received in said raceways, holding clips carried by said trackways at the outer peripheries thereof, and constituting a closure for the space between said trackways, said holding clips being anchored to one of said trackways, an oil seal associated with the other of said trackways and said clips, a closure for the space of said trackways at their inner peripheries, and an oil seal associated with said last mentioned closure.

2. In a turret construction of the character described, a movable trackway formed with a roller raceway, a stationary trackway spaced from said movable trackway and formed with a roller raceway opposite to said raceway on said movable trackway, a roller bearing assembly received in said raceways, a bearing ring carried by said movable trackway and adapted to engage the inner periphery of said stationary trackway, a closure carried by said ring and said movable trackway for closing the space between said trackways, an oil seal associated with said ring and said stationary trackway, holding clips anchored to said stationary track and having flanges engaging said movable track, and an oil seal associated with said flanges and said movable track.

3. In the roller bearing assembly of a turret construction, a roller comprising a main body portion formed with a bore and a counterbore, a thrust collar having a plug extension received in said counterbore, said thrust collar and plug extension being formed with a bore in alignment with the bore in said main body portion, a roller shaft in said bores, and expansion means in said counterbore tending to spread said main body portion and said thrust collar.

4. In the roller bearing assembly of a turret construction, a roller bearing comprising a frusto conical main body portion formed with a cylindrical bore, a counterbore, frusto conical thrust collar constituting a continuation of said main body portion and having a plug extension received in said counterbore, said thrust collar and plug extension being formed with a cylindrical bore in alignment with the cylindrical bore in said main body portion, a roller shaft in said aligned cylindrical bores, an expansion spring in said counterbore tending to spread said main body portion and said thrust collar, and means for preventing relative rotation between said main body portion and said thrust collar.

5. In a turret construction of the character described, an oil seal comprising a sectional ring made up of a plurality of sections with the adjacent sections formed with complementary bevelled ends, said bevelled ends having aligned openings therein, an anchoring bolt passing through each set of aligned openings, and an expansion spring carried by each of said bolts.

6. In a turret construction of the character described, an oil seal comprising a sectional ring made up of a plurality of sections with adjacent sections having complementary bevelled ends, each pair of bevelled ends being formed with aligned openings, an anchoring bolt passing through each set of aligned openings, each of said anchoring bolts having a threaded end whereby it is adapted to be screwed into the trackway of a turret, and a head, and an expansion spring carried by each bolt with each spring interposed between said head and said sectional ring.

7. In the roller bearing assembly of a turret construction, a roller comprising a main body portion formed with a bore and a counterbore, a thrust collar having a plug extension received in said counterbore, said thrust collar and plug extension being formed with a bore in alignment with the bore in said main body portion, a roller shaft in said bores, expansion means in said counterbore tending to spread said main body portion and said thrust collar, and controlling means for said expansion means, whereby said roller may be adjusted.

8. In the roller bearing assembly of a turret construction, a roller comprising a main body portion formed with a bore and a counterbore, a thrust collar having a plug extension received in said counterbore, said thrust collar and plug extension being formed with a bore in alignment with the bore in said main body portion, a roller shaft in said bores, expansion means in said counterbore tending to spread said main body portion and said thrust collar, a shaft in said bores and passing through said spring, and nuts threaded on opposite ends of said shaft and adjustable to vary the relative position of said main body portion and thrust collar.
